[57] CLAIM

The ornamental design for a pacifier medicine dispenser, as shown and described.

DESCRIPTION

FIG. 1 is a perspective view of a pacifier medicine dispenser showing our new design, the broken line showing is for illustrative purposes only and forms no part of the claimed design;

FIG. 2 is a front view thereof;

FIG. 3 is a right side view thereof;

FIG. 4 is a top view thereof; and,

FIG. 5 is a bottom view thereof.
